INVENTOR

UNITED STATES PATENT OFFICE

A. J. WOOD, OF GRAND RAPIDS, MICHIGAN

TREADMILL EXERCISING DEVICE

Application filed August 6, 1928. Serial No. 297,725.

The main objects of the invention are:

First, to provide an improved treadmill exercising device which is very efficient and effectual and noiseless in operation.

Second, to provide an effective control means for such a treadmill.

Third, to provide a means whereby the user of a treadmill exerciser is supported in such manner as to allow the free movement of the 10 arms and entire body when walking or running.

Objects pertaining to details and economies of construction and operation will definitely appear from the description to follow. The 15 invention is clearly defined in the claims.

An embodiment of my invention is shown in the accompanying drawing, in which:

Fig. 1 is a perspective view of my improved exercising device the user being shown by 20 dotted lines.

Fig. 2 is a detail longitudinal section on line 2-2 of Fig. 3, the dotted lines denoting continuity of the plurality of rollers. The adjusting position of the folding elevation 25 blocks is also shown by dotted lines.

Fig. 3 is an enlarged detail cross section on line 3-3 of Fig. 2, parts being shown in full lines.

Fig. 4 is an enlarged detail partial plan 30 view of the roller bearing means with the cover strip removed disclosing the lubricating means for the bearings, which also deadens the sound.

Fig. 5 is a detail partial side view with 35 parts broken away of the adjustably journal bearing block equalizing means for the tread belt.

Fig. 6 is an enlarged detail sectional view on line 6-6 of Fig. 2 showing one of the side 40 guide blocks for the under rim of the endless tread belt.

The parts will be identified by their numerals of reference which are the same in all the views.

1 is the frame of the exercising treadmill. 2 are the side walls inclining toward the rear of the machine. 3 are the end walls. 4 is the top member or frame surrounding the endless tread belt 5. 6 is a plurality of supporting 45 rollers for the tread belt 5. 61 are journal

pins thereon supported in bearings formed by transverse slots in the upper edge of the side walls at 62. In the side wall 2 is formed the longitudinal groove 21 to receive the felt cushion and lubricator strip 22.

The tread belt 5 can be of rubber, canvas, leather or any other suitable material. 7 is an upright standard to the front of the treadmill, supported in socket 71 secured to the top and having socket plate 72 at the bottom. It may be supported in any way. A thumb set screw 73 in the socket 71 retains the standard. The standard 7 is rearwardly curved at 74 carrying the hand bar 75 and having a strap securing means 76, 76 thereto attached.

8 is the rear standard having socket 81 with a thumb screw 82 and socket plate 83 at the bottom thereof. 84 is a hook or stop provided at the top of standard 8. 9 is a pair of straps carrying a belt 92 buckled loosely around the operator. These straps cross at 91 and are attached to opposite ends of the hand bar 75 and connect to the belt on opposite sides of the body. Thus when the body sways to the left the strap at once checks undue movement by a pull on the right grip of the hand bar.

10 is the front guide and control roll for the tread belt 5. Balance wheels 101 have fan blades 102 to produce a retarding action to steady the movement. 103 are journals supporting the balance wheels extending into journal bearings formed in the sides 2. 11 is the belt tightener roll at the rear, the journals 11' of which are supported in adjustable journal bearing blocks 111 impregnated with oil to form a self-lubricating bearing. The bearing blocks are independently adjustable under tension, one at each side to insure proper even tension and running of the tread belt 5. 112 is an adjusting screw having a slotted head 113 to facilitate the adjustment. 114 is the compression spring held yieldingly in engagement with the bearing block 111 by the nut 115 threaded on the screw 112. These parts are arranged on guide way recess 116 in the side wall 2.

117 is the cover plate therefor. 12 is a strip of felt or any other suitable flexible absorbent material impregnated with oil to lubricate the journals of the rollers. This strip is in-

100

serted in the longitudinal groove 21 in the upper edge of the side wall 2. This puts pressure on the journals of the rolls when the cover strip 122 is secured in place. 122 is a cover strip for the bearing section at each side.

13 are belt guides secured to the sides 2. 16, 16 are guide rolls in advance of the guide blocks 13.

10 14 is a distance recording means of a well-known speedometer type, pivotally mounted on the bracket 141. The contact wheel 142 thereof rides on the endless tread belt 5. 15 15 is a plurality of blocks hingedly mounted at 151 to provide a means for adjusting the elevation of the rear end of the treadmill to vary its inclination. In a tread mill exercising device of this kind the effect of continually walking or running uphill is produced. As 20 the operator is supported by the belt 9 around the waist, the operator is free to move his arms and body as in the natural position of walking and in running, thus securing the full effect of such exercise.

25 As the operator walks on the endless belt driven over the plurality of rollers 6, the feet of the operator are continually passing over the rollers producing a vibratory massage effect tending to keep the feet and muscles in proper condition, and, in addition to proper foot exercise, the whole body and all parts are benefited.

30 Because the inclination of the exercising device produces the effect of continually walking up hill, thereby increasing the exercise for the legs and, in conjunction, providing a means of bending in the waist line, full abdominal exercise is secured. To vary the inclination of the exerciser a plurality 35 of blocks 15, hinged together at 151 are provided. The height can be varied by using one block or the plurality as shown by dotted lines in Fig. 2. This varying of the inclination is of a great benefit, for a more obese person is inclined to travel with the belt faster than one of a light build with the exerciser 40 adjusted for the latter.

I desire to claim my invention broadly and also specifically as pointed out in the appended claims.

45 Having thus described my invention, what I claim as new and desire to secure by Letters Patent, is:

50 1. In a tread mill exerciser, the combination of a frame with inclined top, and means of adjusting the incline, a series of transverse rollers with extending journal pins at each end disposed in notches in the upper edges of the side walls of said frame, a longitudinal groove in the said side walls and flexible packing material disposed in said groove and held against said journal pins for delivering lubricant and preventing noise, an endless tread belt disposed around said rollers, a guide control roller in the upper front

part of said casing within said tread belt, a balance wheel fan on the said guide control roller, a tension roller disposed within said tread belt below and to the rear of the said frame with projecting journal pins, independent yieldingly adjustable journal bearing blocks disposed in guide recesses in the side of said casing, upright standards at front and rear of said tread mill, and a strap means and belt for embracing the body of the user 70 with extensions to said front and rear standards to yieldingly support the body of the user, as specified.

2. In a tread mill exerciser, the combination of a frame with inclined top, a series of 80 transverse rollers disposed to support the tread, an endless tread belt disposed around said roller, and a tensioning roller within said tread belt beneath said rollers with independent adjustment for the opposite ends thereof, 85 as specified.

3. In a tread mill exerciser, the combination of a frame with inclined top, a series of 90 transverse rollers disposed to support the tread, an endless tread belt disposed around said rollers, a tensioning roller within said tread belt beneath said rollers with independent adjustment for the opposite ends thereof comprising adjustable bearing blocks, 95 adjusting screws therefor and compression springs on said screws, as specified.

4. In a tread mill exerciser, the combination of a frame with inclined top, a series of transverse rollers disposed to support the tread, an endless tread belt disposed around said 100 rollers, a guide control roller disposed within the upper front part of said frame within said tread belt beneath said rollers, and balance fan wheels on said guide control roller.

5. In a tread mill exerciser, the combination 105 of a frame with inclined top, a series of transverse rollers disposed to support the tread, an endless tread belt disposed around said rollers, a guide control roller disposed within the upper front part of said frame 110 within said tread belt beneath said rollers, and balance wheel means on said guide control roller.

6. In a tread mill exerciser, the combination 115 of a frame with inclined top, a series of transverse rollers disposed to support the tread, an endless tread belt disposed around said rollers and balance control means therefor.

7. In a tread mill exerciser, the combination 120 of a frame with inclined top, a series of transverse rollers disposed to support the tread, an endless tread belt disposed around said rollers and control means therefor.

8. In a tread mill exerciser, the combination 125 of a frame with inclined top, a series of transverse rollers disposed to support the tread, an endless tread belt disposed around said rollers, an upright standard at the front, means carried by said standard embracing 130

the waist of the user to support him yielding-
ly in position.

9. In a tread mill exerciser, the combina-
tion of a frame with inclined top, a series
5 of transverse rollers disposed to support the
tread, an endless tread belt disposed around
said rollers, foldable adjusting blocks to vary
the elevation of one end of the mill to adjust
the incline.
10. In a tread mill exerciser, the combina-
tion of a frame with inclined top, a series of
transverse rollers disposed to support the
tread, an endless tread belt disposed around
said rollers, a driving roller beneath the sup-
15 port rollers, guide blocks at each side of the
under run of the belt in advance of the driv-
ing roller, and guide rolls in advance of said
blocks.
11. In a tread mill exerciser, the combina-
20 tion of a frame with inclined top, a series of
transverse rollers disposed to support the
tread, an endless tread belt disposed around
said rollers, a driving roller beneath the sup-
25 port rollers, guide blocks at each side of the
under run of the belt in advance of the driv-
ing roller.

In witness whereof, I have hereunto set my
hand.

A. J. WOOD.
